Marlowe H. Kluter, Richmond, Ind., assignor to The F. & N. Lawn Mower Company, Richmond, Ind., a corporation of Delaware

Application April 5, 1939, Serial No. 84,069

Term of patent 14 years

To all whom it may concern:

Be it known that I, Marlowe H. Kluter, a citizen of the United States of America, residing at Richmond, in the county of Wayne and State of Indiana, have invented a new, original, and ornamental Design for a Lawn Mower, of which the following is a specification, reference being had to the accompanying drawing, forming part thereof.

Figs. 1, 2 and 3 are a perspective view, a plan view and a cross section of the reel shaft and spider respectively, of a lawn mower embodying the design.

The characteristic features of the present design are shown in solid lines.

I claim:

The ornamental design for a lawn mower, as shown and described.
